INVENTOR
VITA BUCHANAN.

By Conrad A. Deterich
her ATTY.

UNITED STATES PATENT OFFICE.

VITA BUCHANAN, OF NEW YORK, N. Y.

CORSET.

Application filed October 10, 1921. Serial No. 506,632.

My invention relates to improvements in corsets, and the same has for its object to provide a corset which will fit perfectly, be comfortable to the wearer, and which will 5 permit of the same being conformed fully to the figure of the wearer.

Further, said invention has for its object to provide a corset which may be readily adjusted to the figure, and be conformed at 10 its lower rear edges closely to the buttocks of the wearer.

Further, said invention has for its object to provide a corset having separate seat portions which may be severally conformed 15 closely to the buttocks of the wearer so as to leave no ridge or line at the lower edge of the corset which will be visible through the skirt or garment worn over the same.

Further, said invention has for its object to provide a corset having a seat portion 20 formed of one or more elastic inserts, adapted to be conformed closely to the buttocks of the wearer by holding means and attaching members slidably arranged upon said holding means.

Other objects will in part be obvious and in part be pointed out hereinafter.

To the attainment of the aforesaid objects and ends, my invention consists in the novel 25 details of construction, and in the combination, connection and arrangement of parts hereinafter more fully described and then pointed out in the claims.

In the accompanying drawings—

Figure 1 is an illustrative view showing 30 one form of corset constructed according to, and embodying my said invention in position upon the wearer:

Fig. 2 is an outside view of the corset 35 spread out; and

Fig. 3 is a partial back view showing a modified construction in order to adapt the invention to a corset, formed in two halves or parts which is open at both front and 40 back, and the two parts united by lacing.

In said drawings, referring to Figs. 1 and 2, 10 designates a corset which for the purpose of illustrating my invention is herein shown as of the front lace type, that is 45 to say, the back is closed, and the body portion of the corset formed as a unit and secured together along its open front or meeting edges by a suitable lacing 11, and by eyes and hooks 12 and 13, and studs and loops 50 14, 15. The studs and loops 14, 15 being

secured to a separate member 16 which also carries along one of its edges the eyelets to receive the lacing 11.

The body portion of the corset is preferably made of inelastic fabric and is provided at its sides with vertical casings 17, and near the center of the back with a pair of casings 18. 19 denotes a casing arranged along the front of one of the meeting edges of the corset. The said casings 17, 18, 19 are adapted to receive the usual stays.

The lower rear portion of the corset body, which constitutes essentially the seat portion of the garment, is cut away adjacent to the edge thereof intermediate the casings 18, 70 and in place thereof an elastic insert 20 is secured.

The opposite vertical edges of the insert 20 are secured to the corset along the inner opposing edges of the casings 18, while the upper edge of said insert which is curved inwardly is secured along said curved edge to the back portion of the corset intermediate the casings 18.

The lower edge of the elastic insert 20 is 75 reversely curved and has its lower corners extended to form downwardly and outwardly extending elastic members or straps 21, to the ends of which are secured the upper ends of the holding members 22, preferably made of inelastic material in the form of loops which have their other ends secured to the sides of the corset at the lower edges thereof directly below the point where the side casings 17 terminate.

23 denotes attaching members adapted for 80 securement to the upper edge of the stocking of the wearer at the outer side of each leg. The said attaching members 23 are provided at their upper ends with a slotted portion 85 24 through which extend the looped holding members 22 in order to permit of the movement of said attaching members 23 upon said holding members.

The holding members 22 may be provided 100 with adjusting clasps or buckles 25 whereby the length of said holding members 22 may be adjusted to suit the requirements of the wearer.

The body portion of the corset is provided 105 at its front edges directly below the casings 16, 19 with stocking supporters 26, 26' adapted to engage the edge of the stocking at the inner side of the legs of the wearer, and supporters 27, 27' arranged at the front 110

of the corset adjacent to the stocking supporters 26, 26^a adapted to engage the upper edge of the stocking at the front side of each leg.

5 In the modification illustrated at Fig. 3, the invention is essentially the same as that described in connection with Figs. 1 and 2, except that in the construction shown at Fig. 3 the corset is shown as formed in two parts 10 or halves 10^a provided along their adjacent edges 11^a with eyelets and secured together by laces 12^a. The corset is likewise provided adjacent to its back with casings 18^a, and at its sides with casings 17^a. The lower rear 15 corner of each body portion 10^a is cut away to receive an elastic insert 20^a whose inner edges are secured to the lower portions of the casings 11^a, while their opposite corners terminate in elastic straps or members 21^a 20 which are secured to the holding members 22 in the same manner as described in connection with the main construction shown at Figs. 1 and 2.

25 The operation of the corset will be obvious from the foregoing description. It is merely necessary to note that by reason of the fact that the elastic inserts or seat portions being more yielding in vertical and diagonal directions than in horizontal or 30 transverse directions, the instant the same and the straps or members are placed under tension by the holding members and the attaching members thereon, the entire insert whether composed of a single member, as 35 shown at Figs. 1 and 2, or as two members 20^a, as shown at Fig. 3, will be snugly conformed to the buttocks of the wearer and give a perfect finish to the lower edge of the corset.

40 Further, it is to be noted that by making the holding members 22 in the form of loops and rigidly attaching one end thereof to the elastic insert and the other end thereof to an inelastic portion of the corset and 45 slidably disposing the attaching members 23 upon said looped holding members, any strain to which the holding members 22 may be subjected will be instantly communicated to the elastic seat portion and the elastic members extending therefrom.

50 Further, it is to be noted that by arranging the attaching members 23 slidably upon the holding members 22, a greater latitude is afforded for fastening the securing members 23 to the upper edge of the stocking of the wearer.

Having thus described my said invention what I claim and desire to secure by Letters Patent is:

60 1. A corset comprising a body part adapted to be secured together to confine the body of the wearer, an elastic seat, a plurality of holding members each secured at one end to said seat and extending diagonally 65 ally therefrom and secured at its other end

to the corset, and an attaching member carried by each of said holding members adapted to engage with a stocking of the wearer, substantially as specified.

2. A corset comprising a substantially inelastic body part adapted to be secured together to confine the body of the wearer, an elastic seat, a plurality of holding members each secured at one end to said elastic seat and extending diagonally therefrom and at 75 its other end secured to said inelastic body part, and an attaching member carried by each of said holding members adapted to engage with a stocking of the wearer, substantially as specified.

3. A corset comprising a body part adapted to be secured together to confine the body of the wearer, an elastic seat, a plurality of holding members each secured at one end to said elastic seat and extending diagonally 85 downwardly therefrom, and at its other end secured to the body part of the corset and extending vertically downwardly therefrom, and an attaching member movably carried by each of said holding members adapted to engage with a stocking of the wearer, substantially as specified.

4. A corset comprising a body part adapted to be secured together to confine the body of the wearer, an elastic seat, a plurality of adjustable holding members each secured at one end to said elastic seat and extending diagonally downwardly therefrom, and secured at its other end to the body part of the corset, and an attaching member movably carried by each of said holding members adapted to engage with a stocking of the wearer, substantially as specified.

5. A corset comprising a body part 105 adapted to be secured together to confine the body of the wearer, an elastic seat portion, members extending downwardly and forwardly from the opposite ends of said seat portion, a plurality of holding members 110 each secured at one end to one of said downwardly and forwardly extending members, and at its other end secured to the adjacent lower edge of the corset, and an attaching member slidably carried by each of said 115 holding members adapted to engage with a stocking of the wearer, substantially as specified.

6. A corset comprising a body part 120 adapted to be secured together to confine the body of the wearer, an elastic seat, members formed integrally with said seat and extending diagonally downwardly and forwardly from the opposite ends thereof, a plurality of holding members each secured at one end to one of said diagonally extending members and in prolongation thereof, and secured at its other end to the adjacent lower edge of the corset, and an attaching member 125 slidably carried by each of said 130

holding members adapted to engage with a stocking of the wearer, substantially as specified.

7. A corset comprising a body part adapted to be secured together to confine the body of the wearer, a seat portion formed of two parts, means for securing the adjacent edges of said parts together, a member formed integrally with each of said seat parts and extending diagonally from the outer corner thereof, a plurality of looped holding members each secured at one end to

one of said diagonally extending members, and secured at its other end to the side of the body part of the corset adjacent to its lower edge, and an attaching member slidably carried by each of said holding members adapted to engage with a stocking of the wearer, substantially as specified.

Signed at the city of New York, in the county and State of New York, this 23rd day of September, one thousand nine hundred and twenty-one.

VITA BUCHANAN.
